UNITED STATES PATENT OFFICE.

THEODORE A. WILLARD, OF CLEVELAND, OHIO, ASSIGNOR TO THE WILLARD STORAGE BATTERY COMPANY, OF CLEVELAND, OHIO, A CORPORATION OF OHIO.

CONNECTOR FOR STORAGE BATTERIES.

1,191,548.

Specification of Letters Patent. Patented July 18, 1916.

Application filed May 12, 1915. Serial No. 27,482.

To all whom it may concern:

Be it known that I, THEODORE A. WILLARD, a citizen of the United States, residing at Cleveland, in the county of Cuyahoga and State of Ohio, have invented a certain new and useful Improvement in Connectors for Storage Batteries, of which the following is a full, clear, and exact description.

This invention relates to a connector for storage batteries, and its principal object is to provide in a connector having a tapered socket for a tapered terminal member, improved means for preventing the socketed part being spread outwardly by the tapered terminal as the parts are drawn or clamped together.

I accomplish the above object by providing around or on the exterior of the socketed part a reinforcing member, and preferably this reinforcing member is formed as a part of a clamping nut or screw adapted to be drawn tightly onto the exterior of the socketed part of the connector, so that when the nut or screw is tightened to draw the tapered terminal tightly into the socket the outward spreading action is overcome by the inward compressing action of the nut or screw.

My invention may be further briefly summarized as consisting in certain novel combinations and arrangements of parts which will be described in the specification and set forth in the appended claims.

In the drawing Figure 1 is a plan view of a terminal connector, parts being in section; Fig. 2 is a side view of the same; Figs. 3 and 4 are views similar to Fig. 1, showing modifications.

The connector for the storage battery here shown is known as a terminal connector, two of which are adapted to be connected to two of the upstanding posts of the storage battery for the purpose of connecting to the battery the positive and negative flexible leads or conductors. This connector, which is formed of lead, includes a portion 10 having a vertical socket 11 which is preferably composed of upper and lower parts tapered in opposite directions, as shown, the lower tapered part of socket 11 being adapted to receive the upper tapered part of a terminal post of the battery and the upper part of the socket being adapted to receive melted lead when the connector and post are lead-burned together.

At the side of the socketed part 10 is a

lug or boss 12 tapered on the exterior, as shown, and provided also with a tapered socket 13, which receives a correspondingly tapered terminal or terminal member 14 suitably secured to the end of a flexible positive or negative lead or conductor 15.

In each of the constructions here shown the terminal 14 is adapted to be drawn tightly into the tapered socket 13 by a nut or screw having a tapered part which is adapted to fit tightly onto the exterior of the tapered lug or boss 12, so as to counteract the outward spreading action of the terminal 14. In the construction shown in Fig. 1 the terminal is provided with a threaded shank 16 extending outwardly from the end of the terminal beyond the socketed part 12 and the terminal is drawn into tight engagement with the inner wall of the socket 13 by a nut 17 composed of a lead body 17^a provided with a brass or other hard metal insert 17^b, having a threaded hub or central part which is screwed onto the threads of the shank 16, this nut being provided with a flange 17^c tapered on the interior and adapted to be forced down onto the exterior of the tapered part 12, so that as the terminal is drawn tightly in the tapered socket the socketed part is compressed inwardly counteracting the outward spreading action of the terminal.

In Fig. 3 the terminal 14 is provided with a threaded socket, and the terminal is adapted to be drawn into the socketed part 12 by a screw having a threaded shank 18 and a head 19 formed with an inturned flange 19^a, the end part of the screw including the flange being lead covered, the flanged part being internally tapered so as to have a clamping action on the exterior of the socketed member or part 12 as the terminal is drawn into the interior tapered socket 13.

In Fig. 4 the terminal 14 is provided with a stud 21 which is screwed into a threaded socket of the terminal, this stud being threaded on both ends and receiving a nut 22 similar in every way to the nut 17 of Fig. 1, and provided with the tapered flanged part which clamps down onto the exterior of the tapered socket member 12 when the terminal 14 is drawn into the tapered socket.

In each of the three constructions the exterior reinforcing or inward clamping action to counteract the outward spreading of the tapered terminal is precisely the same.

This nut or screw, as the case may be, can be screwed into place by hand or by means of a wrench, the nut in Fig. 1 being provided with a knurled edge and the screw in Fig. 3 5 being shown as provided with a part shaped to receive a wrench.

Having thus described my invention, what I claim is:—

1. A connector for a storage battery having a part provided with a tapered socket, a tapered terminal member fitting into this socket, and means surrounding and engaging the outer surface of the socketed part to overcome the spreading action of the terminal member.
2. A connector for a storage battery, a portion having a tapered socket, a tapered terminal member fitted into the socket, means for drawing said terminal member 10 into the socket and against the tapered wall thereof, said means having a part surrounding the tapered socket and serving to overcome the spreading action of the tapered terminal in the socket.
- 25 3. A connector for a storage battery com-

prising a part having a tapered socket, a tapered terminal member fitting into this socket, threaded clamping means for drawing the tapered terminal member against the tapered wall of the socket, said clamping means having a portion surrounding the socketed part and exerting an inward pressure on the same when the terminal is drawn into place.

4. A connector for a storage battery comprising a part tapered externally and provided with a tapered socket, a tapered terminal fitted into the socket, means for drawing the terminal into the socket and for counteracting the spreading action thereof, 35 comprising a member having a threaded connection with the terminal member having a tapered part which fits tightly onto the outer tapered socketed part.

In testimony whereof, I hereunto affix my 40 signature in the presence of two witnesses.

THEODORE A. WILLARD.
